US00D992167S

(12) **United States Design Patent** (10) **Patent No.:** **US D992,167 S**
(45) **Date of Patent:** **** Jul. 11, 2023**

(54) **REAR LIGHT**

(71) Applicant: **Zhejiang Yinhong Auto & Motorcycle Accessories Co., Ltd.**, Zhejiang Province (CN)

(72) Inventor: **Hang Wang**, Zhejiang Province (CN)

(73) Assignee: **Zhejiang Yinhong Auto & Motorcycle Accessories Co., Ltd.**, Zhejiang (CN)

(**) Term: **15 Years**

(21) Appl. No.: **29/806,637**

(22) Filed: **Sep. 3, 2021**

(51) LOC (14) Cl. **26-06**

(52) U.S. Cl.

(57) **CLAIM**

The ornamental design for a rear light, as shown and described.

DESCRIPTION

FIG. 1 is a perspective view of a rear light showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof; and,

FIG. 8 is an enlarged bottom view thereof.

The broken lines shown on the drawings depict portions of the rear light that form no part of the claimed design.

1 Claim, 8 Drawing Sheets
